UNITED STATES PATENT OFFICE.

WILLIAM PAUL, OF SAMSON, ALABAMA.

RAIL-JOINT LOCK.

1,306,022.

Specification of Letters Patent. Patented June 10, 1919.

Application filed October 31, 1917. Serial No. 199,515.

To all whom it may concern:

Be it known that I, WILLIAM PAUL, a citizen of the United States, residing at Samson, in the county of Geneva and State of Alabama, have invented certain new and useful Improvements in Rail-Joint Locks; and I do hereby declare the following to be a full, clear, and exact description of the invention, such as will enable other skilled in the art 10 to which it appertains to make and use the same.

This invention relates to rail joints, and more particularly to that class of rail joints wherein the use of nuts, bolts and fish plates 15 is entirely dispensed with and the primary object of the invention is to provide a novel type of joint which will not sag in the middle and prevents relative lateral and vertical movement of the adjacent ends of the rail 20 sections.

Another object of the invention is to provide means for connecting the adjacent ends of a pair of rail sections so as to permit slight longitudinal movement of the rails in relation to each other, so as to allow for the 25 expansion and contraction of the metallic rails in hot or cold weather.

A further object of the invention is the provision of means for locking the adjacent 30 ends of the rail sections together and said means providing attaching members for fastening the rail to the tie.

A still further object of the invention is the provision of a rail joint of the above 35 character, which is durable and efficient in use, one that is simple in construction, and one that can be manufactured and placed upon the market at a reasonable price.

With these and other objects in view, the 40 invention consists in the novel construction, arrangement and formation of parts, as will be hereinafter more specifically described, claimed, and illustrated in the accompanying drawings, forming a part thereof in which:

45 Figure 1 is a perspective view of one end of one of the rail sections showing the locking tongue formed thereon.

Fig. 2 is a perspective view of one end of the adjacent rail section.

50 Fig. 3 is a side elevation of the improved rail joint showing the adjacent ends of a pair of rail sections locked together.

55 Fig. 4 is a horizontal section through the improved rail joint showing the fastening plate in position.

Fig. 5 is a transverse section taken on the line 5—5 of Fig. 4.

Fig. 6 is a transverse section taken on the line 6—6 of Fig. 4.

Fig. 7 is a detail perspective view of one 60 of the locking plates for holding the rail sections together, and showing the flanges bent down, and

Fig. 8 is a perspective view of the locking plate showing the flanges positioned vertically 65 before being bent downward into engagement with the rail.

Referring to the drawings in detail, wherein similar reference numerals designate corresponding parts throughout the several 70 views, the numeral 1 indicates the adjacent ends of a pair of rail sections, which are of the ordinary type. Each of the rail sections includes the head or ball 2, the base 3 and a connecting web 4. Each of the rail 75 sections has integrally formed therewith a forwardly extending tongue 5 which engages the head 2 and the base 3 of the adjoining rail section and forms additional support for the head at the joints. The 80 tongues 5 have the lower surfaces cut away as at 6 to provide means whereby the same can readily fit over the base 3 of the rails. By cutting away the under surfaces of the tongues 5 a shoulder 7 is provided, which 85 forms means whereby the bases 3 of the rail sections 1 can engage each other and limit the inward movement thereof. The inner faces of the tongues 5 are formed straight as at 8 so as to engage the vertical web 4 of the rail 90 and the upper and lower edges are preferably inclined inwardly in opposite directions as at 9 to conform to the contour of the head 2 and the base 3 of the rail. A rectangular 95 shaped lug 10 is formed on the inner face of each tongue 5 intermediate the ends thereof and the same is adapted to fit in a longitudinally extending slot formed in the web of each rail adjacent to the rear end of each tongue where the same is formed on the web. 100 The slots 11 are formed a trifle longer than the lugs 10, so as to allow for a slight longitudinal movement of the rail sections 1 in relation to each other and thus allow for the expansion and contraction of the rails. Each 105 of the tongues 5 is provided with a longitudinally extending groove 12 adjacent the lower edge of the same which extends the whole length of the tongue for a purpose which will hereinafter more fully appear.

2

A plurality of tie plates 13 are provided for holding the adjacent ends of the rail sections 1 in locked position after the same have been placed together and each plate 5 comprises a substantially rectangular base plate 14 having a pair of spaced upstanding flanges 15 formed thereon. The flanges 15 are spaced from the side edges of the base plate 14.

10 The tie plates 14 are laid upon the ties (not shown) and suitable spikes (not shown) are driven through the apertures 16 formed in the plate intermediate the side edges and the flanges for holding the plates in position and the adjacent ends of the rails are placed together with the lugs 10 in the slots 11 and then the joint is placed on the tie plates between the upstanding flanges 15. A suitable instrument is then used for bending 15 and forcing the upper edges of the flanges 15 inwardly and into the grooves 12 in the tongues 5, as at 17, which prevent the accidental displacement of the rail sections.

In the foregoing description it can be seen 25 an improved rail joint is provided of simple construction, that absolutely prevents the displacement of the rail sections and also provides means for fastening the rails to the tie.

30 In practice, I have found that the form of my invention, illustrated in the accompanying drawings and referred to in the above description, as the preferred embodiment, is the most efficient and practical; yet realizing the conditions concurrent with the adoption of my device will necessarily vary, I 35 desire to emphasize the fact that various

minor changes in detail of construction, proportion and arrangement of parts may be resorted to, when required, without sacrificing 40 any of the advantages of my invention as set forth.

What I claim as new is:

1. In combination, a rail joint including the abutting ends of a pair of rails, said rails being provided with slots, a tongue projecting longitudinally of each rail and fitting against the side of the other rail, a lug carried by each tongue and interlocking with the slot of the rail, said tongues being provided with longitudinally extending grooves, and a plurality of spaced plates having upwardly extending flanges formed thereon, said flanges being adapted to engage in said grooves, as and for the purpose specified. 45

2. In combination, a rail joint including the abutting ends of a pair of rails, said rails being provided with slots, a tongue projecting longitudinally of each rail and fitting against the side of the other rail, a lug carried by each tongue, said lugs interlocking with the slots of the rails, said tongues being provided with longitudinally extending grooves, and a plurality of spaced plates having upwardly extending bendable flanges 50 formed thereon, said flanges being adapted to engage in the grooves and the rail flanges, as and for the purpose specified. 55

In testimony whereof I affix my signature in presence of two witnesses.

WILLIAM PAUL.
